Patented Jan. 2, 1900.

G. W. REAM.

TOOTH ATTACHMENT FOR CULTIVATORS

(Application filed Dec. 2, 1899.)

UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A TOOTH ATTACHMENT FOR CULTIVATORS.

SPECIFICATION forming part of Design No. 32,066, dated January 2, 1900.

Application filed December 2, 1899. Serial No. 739,055. Term of patent 14 years.

To all whom it may concern:

Be it known that I, GEORGE W. REAM, a citizen of the United States, residing at Canton, in the county of Stark and State of Ohio, ⁵ have invented and produced a new and original Design for a Tooth Attachment for Cultivators, of which the following is a specification.

In the accompanying drawings, illustrating ¹⁰ my design, Figure 1 is a plan view, and Fig. 2 a side elevation.

The leading feature of my design is in the configuration of the parts and their arrangement relative to each other.

¹⁵ A represents a flat metal bar having a portion *a* bent parallel to the main portion, be-

ing bent at *b* and terminating in a free end *c*. The main portion of the bar is bent at an angle, as at *d*, and is again bent at its outer end, as at *e*, into a plane parallel with that of ²⁰ the part A. Near the loop or bend *b* a downwardly-curved depending bracket is secured to the outer face of the plate A, this bracket being shown at B.

What I claim is—

The design for a tooth attachment for cultivators as herein shown and described. ²⁵

GEORGE W. REAM.
